(57) **CLAIM**

The ornamental design for an air conditioner, as shown and described.

DESCRIPTION

FIG. 1 is a front, bottom, left perspective view of an air conditioner of the present disclosure;

FIG. 2 is a front, bottom, right perspective view of the air conditioner shown in FIG. 1;

FIG. 3 is a front elevational view of the air conditioner shown in FIG. 1;

FIG. 4 is a rear elevational view of the air conditioner shown in FIG. 1;

FIG. 5 is a left-side elevational view of the air conditioner shown in FIG. 1;

FIG. 6 is a right-side elevational view of the air conditioner shown in FIG. 1;

FIG. 7 is a top plan view of the air conditioner shown in FIG. 1;

FIG. 8 is a bottom plan view of the air conditioner shown in FIG. 1; and,

FIG. 9 is an enlarged view showing the portion 9 of FIG. 1. The broken lines in FIGS. 1 and 9 define the boundary of the enlargement area and form no part of the claimed design.

The small non-arc shaped lines within the circular openings on the front surface of the air conditioner shown at a lighter line weight than other object lines in FIGS. 1, 2, 3, 8 and 9 form no part of the claimed design.
